UNITED STATES PATENT OFFICE.

DAVID S. KENNEDY, OF BROOKLYN, NEW YORK, ASSIGNOR TO MERGENTHALER
LINOTYPE COMPANY, A CORPORATION OF NEW YORK.

TYPOGRAPHICAL MACHINE.

1,105,667.

Specification of Letters Patent.

Patented Aug. 4, 1914.

Application filed November 29, 1913. Serial No. 803,687.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States, No. 436,532, to O. Mergenthaler, wherein metal slugs or
15 type bars are cast in a mold, and then ejected therefrom between two trimming knives, which insure the parallelism of their opposite side faces and the exact thickness required, one of the knives being adjustably
20 mounted in order that the distance between them may be varied at will. In my previous Letters Patent, No. 1,002,281, the adjusting means are shown as comprising a rotary sector plate provided with adjustable studs
25 to move the knife slide, and an actuating handle by which the sector may be turned to the desired position, and my present improvements are shown more particularly in connection with this specific mechanism. It
30 frequently happens in the use of these devices that after certain adjustments of the knife, the actuating handle projects at the front of the machine in such manner as to interfere with the operator's movements and
35 his free manipulation of the parts.

It is one of the purposes of my invention to obviate this difficulty, by permitting the detachment of the handle and its movement out of the way, without affecting the existing knife adjustment; and similarly, I provide means whereby the handle may be operatively connected to the adjusting means at any one of a plurality of points, thereby materially increasing the convenience and
45 efficiency of the device. I also provide means whereby the handle may be securely locked in all positions, thereby preventing its accidental disengagement and the derangement of the parts. These and other
50 features of my invention will be described in the specification and finally pointed out in the claims.

In the accompanying drawing, I have shown my invention in preferred form and
55 by way of example, and as applied to the

specific style of machine already mentioned, but obviously many changes and variations may be made therein, and in its mode of application, which will still be comprised within its spirit. Generally speaking, I desire it to be understood that I do not limit myself to any specific form or embodiment, except in so far as such limitations are specified in the claims.

Referring to the drawing: Figure 1 is a side elevation, partly broken away, of the knife block, etc., having my improvements applied thereto; Fig. 2 is a section taken substantially on the line 2—2 of Fig. 1; Fig. 3 is a section taken substantially on the line 70 3—3 of Fig. 1; and Fig. 4 is a detached perspective of the indicator plate.

As in my said Letters Patent, the knife A is adjusted to different positions by the adjusting member or rotary sector B provided 75 at its side with a series of studs B¹. The adjusting movement is effected by the handle C, which simultaneously moves the indicator plate E having the pointer E² with relation to the scale F² mounted upon the fixed plate 80 F. The handle C is provided with longitudinally movable pins G passing therethrough and adapted to engage the staggered locking holes F¹ formed in the plate F, and also with the pivoted operating lever 85 D, the farther end of which D¹ engages the heads of the pins G, so that when the lever D is actuated, the pins will be withdrawn from the holes F¹. A spring C¹ is interposed between the lever D and handle C to hold 90 the former in its normal position, and the lever is further provided with leaf springs D² bearing upon the heads of the pins G, to hold the latter in proper relation to the end D¹ of the lever, and to permit a pin to yield 95 in the event of its failure to engage with a locking hole F¹, as indicated by dotted lines in Figs. 2 and 3. The parts so far described, in construction and mode of operation, are substantially the same as those presented in 100 my said Letters Patent, except as hereinafter pointed out.

In the present instance, the handle C, and the parts carried thereby, are relatively movable with reference to the indicator plate E 105 and sector B, which latter are connected so as to rotate together. The plate E is formed with holes E¹ corresponding in number and location to those of the holes F¹ in the fixed plate F, and the plate E is located between 110

the handle C and the plate F (see Figs. 2 and 3) so as to permit the pins G to pass through the holes E¹ and engage the locking holes F¹ at the will of the operator.

- 5 The operation of my improved devices will now be readily understood. Assuming the adjustment and locking of the parts in the extreme position indicated in Fig. 1, the handle C would occupy the dotted line position. In order to shift the handle out of the way, the operating lever D is moved against the force of the spring C¹, and thereby the pin or pins G are withdrawn from both the locking holes F¹ and the holes E¹ of the plate 10 E. The handle C may now be moved to its full-line position, without disturbing the knife adjustment, or the relation of the pointer E² to the scale F². The release of the lever D then permits the spring C¹ to act 15 and the consequent engagement of a pin G with another hole E¹ of the plate E and another locking hole F¹, thereby relocking the member B and indicator in their original position. Similarly, it will be seen that by 20 25 the means described the handle C may be connected to the plate E and sector B in substantially any desired angular relation, thereby materially increasing the convenience of adjustment.
- 30 In order to prevent the accidental disengagement of the locking pin G, and thus to insure the permanence of the knife adjustment, I provide the handle C with a pivotally mounted catch H, so located thereon that it may be interposed between the handle and the operating lever D and prevent the movement of the latter, as shown in Fig. 2, or be turned to inoperative position to permit the free actuation of the lever 35 40 D, as shown in Fig. 3.

As previously stated, I have shown my invention only in preferred form and by way of example, and as applied to a specific style of machine; but obviously many 45 modifications and alterations therein, and in its mode of adaptation, will suggest themselves to those skilled in the art, without departure from its scope.

Having thus described my invention, its 50 construction and mode of operation, what I claim and desire to secure by Letters Patent of the United States, is as follows:

1. A slug trimming mechanism comprising, in combination, a pair of trimming knives adjustable laterally toward and from each other, and a shiftable handle for so adjusting the knives, the said handle being movable at will from its shifted position without disturbing the adjustment of the 55 60 knives.

2. A slug trimming mechanism comprising, in combination, a pair of trimming knives adjustable laterally toward and from each other, a shiftable handle for so adjusting the knives and movable at will from its 65 70 75 80 85 90 95 100 105 110 115 120 125 130

shifted position without disturbing the adjustment of the knives, and means for locking the handle in its new position.

3. A slug trimming mechanism comprising, in combination, a pair of trimming knives adjustable laterally toward and from each other, a shiftable handle to effect the adjustment thereof and movable from its shifted position without disturbing such adjustment, and means for locking the 75 knives in adjusted position.

4. A slug trimming mechanism comprising, in combination, a pair of trimming knives adjustable laterally toward and from each other, a shiftable handle to effect the 80 adjustment thereof and movable from its shifted position without disturbing such adjustment, and means carried by the handle for locking the knives in adjusted position.

5. A slug trimming mechanism comprising, in combination, a pair of trimming knives adjustable laterally toward and from each other, a shiftable handle to effect the adjustment thereof, and an indicator to show such adjustment, the handle being movable 90 from its shifted position without disturbing the indicator.

6. A slug trimming mechanism comprising, in combination, adjustable trimming knives, a shiftable handle to effect the adjustment thereof, a fixed indicating scale, and a movable pointer co-operating with the scale and connected to the handle so as to be operated thereby, the said handle being detachable from the pointer at will to permit the former to be moved from its shifted position without disturbing the position of the latter.

7. A slug trimming mechanism comprising, in combination, a pair of trimming knives adjustable laterally toward and from each other, a member to effect the adjustment thereof, and an operating handle connected to said member, the handle being detachable at will from the member so as 110 to be movable independently thereof and without affecting its position, for the purpose described.

8. A slug trimming mechanism comprising, in combination, a pair of trimming knives adjustable laterally toward and from each other, a movable member to effect the adjustment thereof, and a shiftable operating handle for said member movable at will from its shifted position without affecting the 115 120 125 130 position of the member.

9. A slug trimming mechanism comprising, in combination, a pair of trimming knives adjustable laterally toward and from each other, a movable member to effect the 125 adjustment thereof, and a shiftable operating handle for said member movable at will from its shifted position without affecting the position of the member, and means for locking the member in its moved position.

10. A slug trimming mechanism comprising, in combination, a pair of trimming knives adjustable laterally toward and from each other, a movable member to effect the
5 adjustment thereof, and a shiftable operating handle for said member movable at will from its shifted position without affecting the position of the member, and means carried by the handle for locking the
10 member in its moved position.

11. A slug trimming mechanism comprising, in combination, the adjustable trimming knife A, its adjusting member B, the

plate E connected to said member and carrying the pointer E², and the handle C provided with the pin G passing through said plate and retractable therefrom at will; whereby the handle may be connected with and disconnected from the plate and member when desired.

15
20 In testimony whereof I have affixed my signature in presence of two witnesses.

DAVID S. KENNEDY.
